CLAIM

The ornamental design for a water container with integrated speaker, as shown and described.

DESCRIPTION

FIG. 1 is a first perspective view of a water container with integrated speaker showing my new design; FIG. 2 is a second perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view thereof; and, FIG. 8 is a bottom plan view thereof.

The broken lines in the drawings illustrate portions of the water container with integrated speaker which form no part of the claimed design.
